US0D1006687S

(12) **United States Design Patent** (10) **Patent No.:** **US D1,006,687 S**
(45) **Date of Patent:** **** Dec. 5, 2023**

(54) **FAIRING FOR MOTORCYCLES**

(71) Applicant: **PIAGGIO & C. S.P.A.**, Pontedera (IT)

(72) Inventors: **Marco Lambri**, Pontedera (IT); **Davide Cattaneo**, Pontedera (IT)

(73) Assignee: **PIAGGIO & C. SPA**, Pontedera (IT)

(**) Term: **15 Years**

(21) Appl. No.: **35/515,514**

(22) Filed: **Apr. 29, 2022**

(80) **Hague Agreement Data**

Int. Filing Date: **Apr. 29, 2022**

Int. Reg. No.: **DM/220590**

Int. Reg. Date: **Apr. 29, 2022**

Int. Reg. Pub. Date: **Nov. 4, 2022**

(30) **Foreign Application Priority Data**

Nov. 16, 2021 (EM) 008761043

(57) **CLAIM**

The ornamental design for a fairing for motorcycles, as shown and described.

DESCRIPTION

1.1 is a front and left side perspective view of a fairing for motorcycles embodying our new design;

1.2 is a front elevation view thereof;

1.3 is a front and right side perspective view thereof;

1.4 is a left side elevation view thereof;

1.5 is a right side elevation view thereof;

1.6 is a top plan view thereof; and

1.7 is a bottom plan view thereof.

The broken lines in the reproductions illustrate portions of the fairing for motorcycles that form no part of the claimed design.

1 Claim, 7 Drawing Sheets
